SHIRT

Deckerd J. Gray, Ware Shoals, S. C., assignor to
 Riegel Textile Corporation, New York, N. Y., a
 corporation of New York

Application December 22, 1934, Serial No. 758,780

2 Claims. (Cl. 223—37)

This invention relates to shirts—specifically, to men's and boys' ready-to-wear shirts—, and the object thereof is to provide neat, efficient and convenient means for retaining in folded condition a shirt as usually folded for transportation and sale.

It is the customary practice, in preparing shirts for the trade, especially where several shirts are to be placed in a single package, to fold each shirt in some specific way about a cardboard form and to secure each fold as made and finally the complete folded shirt by pins inserted therein, the cuffs, which it is usually found desirable to display, being each folded from the side over the front of the shirt and secured thereto by a pin stuck through the back and concealed by the front of the cuff. From ten to twelve pins at least are used for the purpose, and not only does the insertion of these pins take time and so constitutes an item of expense but, and of greater consequence, their removal by the purchaser of a shirt takes even more time and frequently causes exasperation since the pins are all concealed and it is often difficult to find the headed end of a pin even after the pin itself has been located.

My present improvement, by which I have eliminated the objectionable use of pins for the purpose, comprises briefly stated, a retaining band 30 of paper or other suitable material, which is wrapped around the folded shirt and is fastened at the front thereof, as by a buttonhole, loop or the like, to a button of the shirt, usually and preferably the button immediately below the neckband of the shirt whether with attached or for detached collars, and at the back has its two ends fastened together and to the inwardly folded tail of the shirt, by a single pin for example; and where the cuffs are displayed they are fastened as usual to the front side folds of the shirt but by clips which will be detached by merely drawing the cuffs away from the shirt and will then drop out.

The invention will be understood by reference 45 to the accompanying drawing, in which Figure 1 shows in front or face view and Fig. 2 in longitudinal section, a folded shirt with my new re-

taining band in place thereon and with its cuffs secured thereto by clips.

As therein illustrated, 1 designates the shirt and 2 designates the encircling retaining band. At the front of the shirt the band is fastened to the 5 button 3—by means of a buttonhole or slit 4, preferably formed as shown in an inner length or section 5 of the band so as to be concealed from view, and at the back its two ends are pinned together and to the upwardly extending and inwardly folded tail 6 of the shirt by the single pin 7. Each cuff 8 is held in place by a clip 9 which fastens its inner side to the front side fold of the shirt.

It is apparent that by its attachment to the 15 button on the front of the shirt the retaining band will be held against displacement lengthwise of the shirt and hence will hold up and in place at the back the upwardly extending and folded tail of the shirt; and, further, that on removing the single pin and stripping off the band and pulling out the cuffs to detach the clips the shirt will be ready for use.

The buttonhole can of course be formed in the main body of the retaining band if it is not 25 desired to conceal it and, in place of a buttonhole, the band can be secured to the button by an elastic loop, spring clip, or other suitable means. The invention can also be further modified, in its several details, within the scope of the appended claims, without departing from the spirit 30 or sacrificing the substantial advantages thereof.

What I claim as new, and desire to secure by Letters Patent, is—

1. As a new article of manufacture, a folded 35 shirt and a retaining band surrounding the same and attached at the front to a button thereof and at the back having its ends attached together and to the tail of the shirt.

2. As a new article of manufacture, a folded 40 shirt and a retaining band, said band surrounding the shirt and having intermediate its ends a buttonhole by which it is attached at the front to one of the upper buttons of the shirt and at the back has its two ends pinned together and 45 to the tail of the shirt.
